(57) **CLAIM**

The ornamental design for a base for figurine, as shown and described.

DESCRIPTION

FIG. 1 is a front left perspective view of a base for figurine showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom rear perspective view thereof; and,

FIG. 9 is a bottom front perspective view thereof.

The portions of the drawings appearing in even length dashed broken lines are for environment only and do not form a part of the claimed design.

The solid jagged lines represent the removal of a portion of unclaimed environment only and do not form a part of the claimed design.

1 Claim, 5 Drawing Sheets

FIG. 1

FIG. 2**FIG. 3**

FIG. 4**FIG. 5**

FIG. 6

FIG. 7

FIG. 8

FIG. 9
